UNITED STATES PATENT OFFICE.

VIRGINIA WHITTINGTON, OF VALDOSTA, GEORGIA.

LADY'S NEGLIGÉE UNDERGARMENT.

1,073,724.

Specification of Letters Patent. Patented Sept, 23, 1913.

Application filed October 24, 1912. Serial No. 727,574.

To all whom it may concern:

Be it known that I, VIRGINIA WHITTINGTON, a citizen of the United States, residing at Valdosta, in the county of Lowndes and State of Georgia, have invented a new and useful Lady's Negligée Undergarment, of which the following is a specification.

One object of this invention is to provide a woman's negligée undergarment, comprising a chemise and drawers, the garment being fashioned from a minimum number of sections.

With the foregoing and other objects in view which will appear as the description proceeds, the invention resides in the combination and arrangement of parts and in the details of construction hereinafter described and claimed, it being understood that changes in the precise embodiment of invention herein disclosed, can be made within the scope of what is claimed, without departing from the spirit of the invention.

In the drawings:—Figure 1 shows the invention in front elevation; Fig. 2 is a rear elevation; and Fig. 3 is a bottom plan, looking upwardly into the crotch of the drawers.

In constructing a negligée garment in accordance with the present invention, a minimum number of pieces of cloth are employed, one piece, hereinafter referred to as the front section, being denoted by the reference character 1; the other piece, hereinafter referred to as the rear section, being denoted by the reference character 2. The sections 1 and 2 are provided at their upper ends with tabs 3, united along the seams 4 to form the arm holes of the chemise portion of the garment. The longitudinal edges of the sections 1 and 2 are united along seams 5 to define the side seams of the garment, the side seams being extended from the arm holes downwardly to the lower end of the chemise portion of the garment. The lower ends of the sections 1 and 2 are united in their central portions only, along a seam 6, to define the crotch of the drawers. Ruffles 7 are secured as at 7^a to the lower ends of the sections 1 and 2 to define the legs of the drawers. The ends of the ruffles are united along a seam 7^b, in alignment with the seam 6.

The seat of the drawers is transversely continuous, as shown at 8, the rear section 2 being provided with an inverted plait 9, 55 located above the seat of the drawers, the plait 9 serving to give sufficient fullness to the garment. The upper end of the plait 9 is stitched down as indicated at 10.

The upper portion of the rear section 2 is 60 split and stitched together as indicated at 11, so as to shape the chemise portion of the garment. The front section 1 may be provided, adjacent its top, with an opening 12, which may be closed by a tie string 14. 65 This detail, however, is non-essential.

It is to be observed that the garment herein disclosed comprises a chemise and a pair of drawers in a single garment. Moreover, the garment is of exceedingly simple 70 construction and may be manufactured at a minimum expense, the operation of cutting the cloth being reduced to a minimum.

The garment herein disclosed does not fit closely to the body, but is loose and flowing. 75 It is well adapted, without alterings of any sort, to serve as a maternity garment.

The garment herein disclosed is cool and is sanitary. No buttons or pins are required for securing it in place. When the 80 garment is once adjusted for wear, it need not be removed until disrobing at night. It is to be noted that owing to the construction and dimensions of the parts of the garment, there is no necessity for forming 85 openings at the rear thereof or at the front, adjacent the crotch.

The garment is semi-fitting, to be held in position around the shoulders with a drawstring. 90

Having thus described the invention, what is claimed is:—

A chemise, the body portion of which consists of two pieces of material only, comprising a front section and a back section, 95 the longitudinal edges of the sections being secured together to form the side seams of the chemise, the intermediate portions only of the lower edges of the sections being secured together to form leg openings, the 100 back section being folded toward the longitudinal center of the chemise to form a pair of plaits, the upper edges only of the plaits being stitched down and the plaits at their

lower ends tapering and running out into the constituent material of the back section, the back section being split and sewed together above the plaits to take up the slack
5 caused in the upper portion of the chemise by the formation of the plaits.

In testimony that I claim the foregoing

as my own, I have hereto affixed my signature in the presence of two witnesses.

VIRGINIA WHITTINGTON.
